CLAIM

The ornamental design for a carbine stock, as shown and described.

DESCRIPTION

FIG. 1 is a left view thereof of a carbine stock showing our new design;

FIG. 2 is a right view thereof;

FIG. 3 is a rear side view thereof;

FIG. 4 is a front side view thereof;

FIG. 5 is a top plan view thereof;

FIG. 6 is a bottom plan view thereof; and,

FIG. 7 is a perspective view thereof.

The broken lines shown in the drawings are for illustrative purposes only and form no part of the claimed design.
